UNITED STATES PATENT OFFICE.

HARRY KALNIANCZYN, OF NAUGATUCK, CONNECTICUT.

DESIGN FOR A POCKET ARTICLE.

48,065.

Specification for Design.

Patented Nov. 2, 1915.

Application filed September 3, 1915. Serial No. 48,892. Term of patent 7 years.

To all whom it may concern:

Be it known that I, HARRY KALNIANCZYN, a subject of the Emperor of Austria-Hungary, residing at Naugatuck, in the county of New Haven and State of Connecticut, have invented a new, original, and ornamental Design for a Pocket Article, of which the following is a specification, reference being had to the accompanying drawing, forming part thereof.

The figure is a view in perspective of a pocket article, showing my new design.

I claim:

The ornamental design for a pocket article, as shown.

HARRY KALNIANCZYN.

Witnesses:

ROBERT D. BEARDSLEY,

JOHN P. GUBBINS.
